HAND WHEEL

Robert C. Stanley, 297 Canton St., Westwood, Mass.

Filed Dec. 31, 1963, Ser. No. 77,989

Term of patent 14 years

(Cl. D78—1)

FIG. 2.

FIG. 3.

FIG. 1 is a top plan view of a hand wheel, showing my new design;

FIG. 2 is a side elevational view thereof; and

FIG. 3 is a vertical sectional view substantially on the line and in the direction of the arrows 3—3 of FIG. 1, showing the outer contours of the hand wheel.

The dominant features of my design reside in the portions shown in full lines.

I claim:

The ornamental design for a hand wheel, substantially as shown and described.
